UNITED STATES PATENT OFFICE.

FRANK J. O'BRIEN, OF BALTIMORE, MARYLAND.

SANITARY CAN CLOSURE.

Application filed May 17, 1922. Serial No. 561,641.

To all whom it may concern:

Be it known that I, FRANK J. O'BRIEN, a citizen of the United States, residing at the city of Baltimore and State of Maryland, have invented certain new and useful Improvements in Sanitary Can Closures; and I do hereby declare the following to be a full, clear, and exact description of the same, reference being had to the accompanying drawings, forming part of this specification.

This invention relates to new and useful improvements in can closures and has for its object the provision of a container having a frictionally held cover hermetically sealed before the can is filled and which, after the can is once opened, may be replaced to form a practically air-tight closure.

A further object of the present invention is to simplify the method of making friction can closures and particularly the beading of the outer periphery of the cover. In the so-called sanitary cans now on the market and in which the entire top is removable after breaking the seal, the marginal edge of the cover is sharp and often causes a scratch or cut when prying it off the container, and it has been found impractical to form an effective seal which would include a beaded edge so that injury on removing the cover would be entirely obviated. In practicing the preferred method described herein the removable cover of the can is secured to the container by a single operation consisting of two steps (although the two steps may be separate operations performed on separate machines), the first of which positions the gasket and compresses it, and the second step of the operation follows immediately thereafter, and beads the outstanding flange or skirt of the cover and adds compression to the already positioned gasket to form the seal.

In the drawings—

Figure 1 is a vertical section through a portion of the can with the first spinning roller just engaging the cover.

Fig. 2 is a similar view at the end of the movement of the first spinning roller.

Fig. 3 shows the second spinning roller beginning its movement.

Fig. 4 shows the second spinning roller at about the middle of its operation.

Fig. 5 shows the parts in the final position with the can seam completed and the spinning roller ready to be withdrawn.

It is customary in the art of making cans

having removable tops or covers, to apply the removable cover in the can factory and to apply the permanent cover in the packing factory and the invention will be described in accordance with that practice, although it should be understood that the invention is equally applicable to other systems wherein, for example, the removable cover is the last to be applied.

The container body 10 is usually open at both ends and is in the form of a hollow cylinder formed from a rectangular sheet of tin seamed and soldered along a line parallel to its axis. The cover 11 is pressed from a disk of tin so as to form a central dome 14 surrounded by a valley portion 15 forming an annular stiffening rib. Before spinning, the cover has its marginal portion bent to form a rectangular channel formed by the vertical upstanding portion 16, the central portion 17 forming the inverted bottom of the channel and a downwardly extending vertical portion 18 which forms the outside cylindrical edge of the cover.

A gasket 20 of rubber or other similar material is affixed to the cover in any preferred manner as by adhesive, for example, in case a ring of the usual type is employed, or this gasket 20 may be formed by depositing a layer of liquid rubber composition in the corner of the cover as shown.

The container body is placed on the usual spinning table (not shown) and the cover is placed on the chuck 24 which is rotated at a high speed as is customary in the art. The upward movement of the spinning table carrying with it the container body, in conjunction with the spinning roller action hereafter described, flares the container body as at 25 and brings the cover into snug engagement with the body. The first spinning roller 27 is moved transversely to its axis which is always parallel to the axis of the can, this action bringing the annular rounded projection 28 into contact with the side portion 18 at a point slightly below the center of the latter, the smooth horizontal edge 29 of the spinning roller engaging the upper surface of the channel bottom 17.

Continued movement of the roller indents the edge 18 as at 30 of Fig. 2 deforming and compressing the gasket 20 against the outer surface 31 of the container body 10. The diameter of the extreme edge 32 of the can cover is not appreciably changed during this process since the curved surface 33 of

the first spinning roller permits the edge to maintain its lateral position, although directing it outwardly, i. e., away from the plane of the top of the container and causes 5 the outer margin of the cover to assume the outwardly directed flared conical form best seen in Fig. 3. During this action the flaring of the upper edge of the can body is practically completed.

10 The first spinning roller is now withdrawn and the second spinning roller 35 is advanced in the same way as the first, the edge 32 first engaging the inclined spinning surface 36 which curls the edge 32 upwardly 15 into the groove 37, the upper wall 38 of which causes the peripheral edge of the cover to turn through an arc so as to direct it nearly parallel to the can body, thus forming a bead 39. At the same time the 20 projection 40 engages the central portion 41 of the outside edge of the cover and insures that such portion is indented sufficiently to compress the gasket 20 to the desired degree.

25 The closure edge thus formed is perfectly smooth on the outside having an upper smooth curved edge 42 slightly flared and having a smooth lower beaded edge 39 on neither of which it is possible to cut the hand in the act of removing the cover or on 30 replacing the cover after use.

The finished cover has a central dome 14, an annular stiffening rib 15, a cylindrical portion 16, a flat portion 17 having a marginal bead 42, which with the inwardly directed incline 44, the cylindrical portion 40 and the closed bead 39, form an annular flange which is spaced from the wall of the can to accommodate the gasket 20, the latter 40 entirely filling the upper half of the channel between the flange and the can.

In order to remove the contents of the container for the first time the gasket 20 is removed in the usual manner after which 45 the cover is held to the container merely by the friction between the portion 16 of the cover and the flared top of the container so that the cover may be readily lifted off by a slight amount of force, part of the contents removed, and the cover replaced by pushing it directly downward over the container body to form the customary friction fit.

What I claim is:—

55 1. The method of sealing a cover on a can which consists in forming a downwardly directed channel in the cover, applying a gasket within said channel, applying said cover to a container, indenting a central portion of the outer wall of the channel of the cover to compress the gasket against the container and to flare the edge portion of the cover outwardly and downwardly, and in spinning such outwardly flared portion of the cover to form a bead.

2. The method of closing a cover on a container which consists in applying a gasket to the cover, placing the cover on the container, spinning the cover flange until the gasket is compressed against the container, and in then spinning the margin of the cover flange to form a beaded edge.

3. A can seam including a flare container, a cover frictionally engaging the container and extending beyond the wall of the container parallel to the top of the container and then turned downward to form a channel, the outer wall of said channel being spaced from the container wall a sufficient distance to permit easy removal of the cover over the flared edge of the container, the lower edge of said cover being turned upward and inward to form a bead, and a gasket between the outer wall of the channel and the outer surface of said container.

4. A gasketed can seam comprising a container, a gasket, and a removable and replaceable cover; characterized by the cover having a downturned outer flange one side centrally indented to engage the gasket to compress it against the wall of the container, said flange having a beaded edge.

5. A gasketed can seam comprising a container, a gasket, and a removable and replaceable cover; characterized by the cover having a downturned outer flange one side centrally indented to engage the gasket to compress it against the wall of the container, said flange having an upturned beaded edge.

6. A container cover having an annular inverted channel, the outer surface of the inner wall of the channel engaging the inner surface of the wall of the container, and the inner surface of the outer wall of the channel being spaced from the wall of the container, said outer wall being further indented centrally and having a beaded edge.

7. A container cover of the friction type characterized by the provision of an inverted margin forming a beaded edge, the inner diameter of said edge being sufficiently greater than the outside diameter of the container mouth to permit easy replacement of the cover on the container with the beaded edge surrounding the container.

8. A cover comprising a top having an annular flange formed with an inward incline, a beaded edge, and a cylindrical portion connecting said incline with said edge.

9. A cover comprising a top having an annular flange formed with an inward incline, a beaded edge, and a cylindrical portion connecting said incline with said edge, the outside diameter of said beaded edge being greater than the greatest diameter of said incline.

10. A friction type can cover comprising a top having a can receiving channel formed of a plurality of substantially vertical walls,

the inner of which is adapted to engage the inner surface of the can and a horizontal portion having a beaded margin connecting said vertical walls.

5 11. A friction closure of rigid sheet metal having a beaded margin, a closed beaded edge, and an indented portion connecting said beads.

12. A closure comprising a sheet of metal

having a central dome, an annular stiffening rib, a vertical container engaging wall, a horizontal portion adapted to engage the top of the container, a bead forming the upper outer edge of the closure, a vertical gasket engaging wall and a bead at the 15 lower end of said wall.

FRANK J. O'BRIEN.
